R. M. SMITH.

FLYING MACHINE.

APPLICATION FILED JUNE 26, 1911. RENEWED OCT. 15, 1914.

1,118,375.

Patented Nov. 24, 1914.

UNITED STATES PATENT OFFICE.

REXFORD M. SMITH, OF WASHINGTON, DISTRICT OF COLUMBIA, ASSIGNOR, BY MESNE ASSIGNMENTS, TO CONNECTICUT AIRCRAFT COMPANY, OF NEW HAVEN, CONNECTICUT, A CORPORATION.

FLYING-MACHINE.

1,118,375.

Specification of Letters Patent. Patented Nov. 24, 1914.

Original application filed September 30, 1909, Serial No. 520,240. Divided and this application filed June 26, 1911, Serial No. 635,272. Renewed October 15, 1914. Serial No. 866,882.

To all whom it may concern:

Be it known that I, REXFORD M. SMITH, a citizen of the United States, residing at Washington, in the District of Columbia, 5 have invented new and useful Improvements in Flying-Machines, of which the following is a specification.

This invention relates to flying machines of the heavier than air type, the present application being a division of my prior application filed September 30, 1909, Serial No. 520,240.

The object of the invention is to provide reliable means for maintaining a perfect 15 equilibrium in the air without mental effort and without either voluntary or involuntary physical effort on the part of the aviator.

With the above and other objects in view, 20 the nature of which will more fully appear as the description proceeds, the invention consists in the novel construction, combination and arrangement of parts as herein fully described, illustrated and claimed.

25 In the accompanying drawings:—Figure 1 is a side elevation of a flying machine embodying the present invention. Fig. 2 is a vertical cross-section through the same on the line 2—2 of Fig. 1 looking forward. 30 Fig. 3 is a detail rear elevation of the aviator's seat showing a slight modification.

The frame of the machine which extends fore and aft, comprises the four main longitudinal bars 1, 2, 3 and 4, each of which, as 35 shown in Fig. 1, comprises a pair of members or strips 5 and 6 which are preferably connected together at their opposite ends, at the bow and stern of the machine, the said members or strips being spaced apart 40 by means of transverse struts 7 arranged at suitable intervals, while between the struts, the members 5 and 6 are connected and held together and braced by diagonal truss wires 8. This makes a strong and exceedingly 45 light frame bar admirably adapted for the support of the front and rear planes and controlling devices.

9 designates stanchions or cross bars connecting the main longitudinal frame bars 1 and 2 at suitable intervals, while 10 designates diagonal truss wires for bracing the frame.

The main lifting and supporting wings 11 project laterally outward from the central portion of the main frame, being arranged one above the other as shown in Figs. 1 and 2, thus making the machine, in the illustrated embodiment, of the biplane type. Arranged at the rear of the main frame, are the rear or tail-planes 12, preferably two in number, arranged one above the other, and mounted in fixed relation to the frame. It will be observed that these planes 12 are preferably curved so as to constitute auxiliary lifting planes, thereby adapting 65 them to compensate for the weight of the rear portion of the main frame and assist the main planes 11 in the uplift of the machine.

The front planes 13, arranged at the forward end of the main frame, are also preferably curved from front to rear for a similar purpose and are connected together for simultaneous movement by stanchions 14 and also, if desired, by diagonal braces 15. 75 The framework connecting the front planes 13 is pivotally mounted at 16 on a suitable supporting frame bar 17 and provided with an operating lever arm 18 from which a connecting bar or rod 19 extends rearward 80 where it is pivotally connected to the upper end of a control lever 20 fulcrumed at 21, intermediate its ends and having a hand wheel 22 mounted and journaled on the lower end thereof as shown in Fig. 1. The 85 lever 20 is held in a central or neutral position by any suitable means such as opposing springs 23 and 24 which permit the lever to be vibrated either forward or backward to operate the connecting rod 19 and thereby 90 vary the angle of inclination of the front planes 13 in order to ascend or descend.

Connected pivotally to the rear end of each of the side members of the main frame is a rudder 25, the same being mounted on a 95 vertical axis or hinge rod 26 so as to swing horizontally. Each rudder is provided with a forward extension 27 which acts as a partial counter-balance for the main body of the rudder. The two rudders 25, which are 100 arranged in transverse alignment with each other, will, in practice, probably be connected together so as to move in unison and maintain their parallelism and one or both

of said rudders, will be provided with a tiller arm 28 from which a suitable flexible connection, (not shown) will extend to a drum or pulley 29 on the hub of the controller wheel 22. The operating connections for the rudders 25 and the front planes 13 will all be connected to and be controlled by the wheel 22 so that by turning said wheel to the right, the rudders will be positioned 10 at any angle adapting them to steer the machine to the right and vice versa and by pressing the wheel 22 forward the planes 13 will be inclined to direct the machine upward, while, by moving the wheel 22 backward the planes 13 will be inclined so as to direct the machine downward.

The aviator's seat 30 is mounted so that it is free to move laterally with respect to the length of the machine. This seat may either 20 be mounted on suspending swing links 31 as shown in Figs. 1 and 2 or it may be mounted on caster wheels or rollers 32 adapted to travel on one or more track rails 33. The object in making the aviator's seat 25 movable is to automatically control the lateral balancing planes 34 which are preferably arranged above the upper main plane 11 as shown in Figs. 1 and 2 and pivotally mounted on extensions 35 of the stanchions 30 36 which connect the upper and lower main planes 11. From the forward edge of one of the planes 34, a flexible connection or cable 37 extends around pulleys 38 to the corresponding front edge of the other plane 34, and a flexible connection or cable 39 extends from the rear part of one of the planes 34 around suitable guide pulleys 40 to the other balancing plane 34. At an intermediate point the connection or cable 39 is 40 attached at the point 41 to the upper arm of a lever 42 fulcrumed at 43 and having a jointed connection at 44 with the aviator's seat. It will now be apparent that as the machine starts to incline to one side or the 45 other the relative movement between the machine frame and the aviator's seat will effect a pull on one of the flexible connections referred to, thereby effecting a corresponding variation in the angles of the lateral balancing planes, causing the latter to 50 counteract instantly the tendency of the machine to list or incline away from a true horizontal plane. This is accomplished without any mental effort whatever on the 55 part of the aviator and also without voluntary or involuntary physical effort on his part.

45 designates centrally located vertical fins for maintaining the direction of travel 60 of the machine and overcoming lateral leeway.

Instead of employing the lever 42 above referred to, the flexible connection 39 or the connection 37 may be passed around guide

65 pulleys and connected directly to the aviator's seat 30 as indicated in Fig. 3.

Having thus described the invention, what I claim as new is:

1. In an aeroplane, the combination of a main plane, propelling devices carried thereby, a lateral dip controlling means, a laterally swinging aviator's seat, and a motion transmitting element movably supported by the main plane independently of the aviator's seat, said motion transmitting element being connected with said lateral dip controlling means and having a shiftable connection with the aviator's seat for receiving motion therefrom. 75

2. In an aeroplane, the combination of a main plane, propelling devices carried thereby, a lateral dip controlling means, a laterally swinging aviator's seat, and a lever pivotally supported upon the main plane independently of the aviator's seat and connected with said dip controlling means, said lever having a shiftable engagement with the seat for receiving motion therefrom. 80

3. In an aeroplane, the combination of a main plane, propelling devices carried thereby, a lateral dip controlling means, a laterally swinging aviator's seat flexibly supported from the main plane, and a lever intermediately pivoted upon the main plane independently of the aviator's seat, said lever 90 being connected at its upper end to the lateral dip controlling means and shiftable connected at its lower end with the aviator's seat for receiving motive power therefrom. 95

4. In an aeroplane, the combination of a main plane, propelling devices carried thereby, a lateral dip controlling means, an aviator's seat, links or the like flexibly supporting said seat for lateral motion from the main plane, and a lever pivotally supported upon the main plane independently of the aviator's seat, said lever being connected at its upper end with the lateral dip controlling means and shiftable connected at its lower end with the aviator's seat to 100 receive motion therefrom. 105

5. In an aeroplane, the combination of a main plane, propelling devices carried thereby, a lateral dip controlling means, a laterally swinging aviator's seat, and a lever pivoted to the main plane independently of the aviator's seat, said lever being connected with said lateral dip controlling means and slidably and pivotally coupled to the 115 aviator's seat. 120

6. In an aeroplane, the combination of a main plane, propelling devices carried thereby, lateral balancing devices, cables leading therefrom, an aviator's seat, links suspending said aviator's seat from the main plane 125 for lateral swinging motion, and a normally upright lever intermediately pivoted to the main plane at a point above the level of the

aviator's seat, said lever being connected at its upper end to said cables and slidably and pivotally connected at its lower end to the aviator's seat.

- 5 7. In an aeroplane, the combination of a main plane, propelling devices carried thereby, a lateral dip controlling means, a lateral swinging aviator's seat, links suspending said aviator's seat from the main plane for lateral swinging motion, and a normally upright lever intermediately pivoted to the main plane at a point above the level of the aviator's seat, said lever being connected at its upper end to said dip controlling means 10 and slidably and pivotally connected at its lower end to the aviator's seat.
- 15 8. In an aeroplane, the combination of a

main plane, propelling devices carried thereby, a lateral dip controlling means, a lateral swinging aviator's seat, downwardly diverging links suspending said aviator's seat from the main plane, and a normally upright lever intermediately pivoted to the main plane at a point above the level of the aviator's seat, said lever being connected at its 20 upper end to said dip controlling means and slidably and pivotally connected at its lower end to the aviator's seat.

In testimony whereof I affix my signature in presence of two witnesses.
